UNITED STATES PATENT OFFICE.

ERVAN V. ALLEN, OF BOGALUSA, LOUISIANA.

CULTIVATOR.

1,378,165.

Specification of Letters Patent. Patented May 17, 1921.

Application filed August 9, 1918. Serial No. 249,083.

To all whom it may concern:

Be it known that I, ERVAN V. ALLEN, a citizen of the United States, residing at Bogalusa, in the county of Washington and 5 State of Louisiana, have invented certain new and useful Improvements in Cultivators; and I do hereby declare the following to be a full, clear, and exact description of the invention, such as will enable others 10 skilled in the art to which it appertains to make and use the same.

The object of the invention is to provide a relatively inexpensive and efficient cultivator construction having a framework 15 made up essentially of metal while having the maximum strength with the minimum weight to insure durability while imposing the least possible effort and strain upon the operator in guiding or directing the same 20 while in use; and furthermore to provide an apparatus for the purpose indicated with reference to which a relatively wide range of cultivating shovels may be used, so as to extend the utility of the device to meet 25 the various needs of the farmer.

Further objects and advantages will appear in the following description, it being understood that changes in the form, proportion and details of the illustrated embodiment of the invention may be resorted to, within the scope of the appended claim, 30 without departing from the spirit of the invention.

In the drawing:

35 Figure 1 is a side view of a cultivator constructed in accordance with the invention,

Fig. 2 is a plan view of the same,

Fig. 3 is a transverse section on the line 40 3-3 of Fig. 1,

Fig. 4 is a horizontal sectional view on the plane indicated by the line 4-4 of Fig. 1,

Fig. 5 is a transverse sectional view on 45 the plane indicated by the line 5-5 of Fig. 1,

Fig. 6 is a front view of the forward shovel and standard.

The structure illustrated embodies essentially 50 the main central longitudinal beam 10, to the forward end of which is attached the draft appliance 11, the rearwardly divergent relatively adjustable side beams 12, which carry the plow standards 13 and are 55 connected pivotally at their forward ends to the beam, and a transverse adjustable or

extensible connection 14 between the rear ends of said side beams and the main beam, and handles 15, which are supported at intermediate points by braces 16 from the 60 main beam and are attached at their forward ends to the upper extension of a standard 17, which supports the forward supporting wheel 18. The main beam preferably consists of parallel metallic bars 10^a 65 and 10^b, spaced laterally to receive the above-mentioned standard 17, and a standard 19 of the rear supporting and guiding wheel 20, a spacing block 21 being interposed between said bars at their rear extremities, a forward standard 22 being interposed therebetween near their forward ends, and a draft bar or tongue 23 being interposed between and secured to the same in advance of the standard 22, and having 70 the above mentioned draft appliance 11 carried thereby. Supported by said parallel bars or elements 10^a and 10^b of the main beam are the upper and lower plates 24 secured by vertical bolts 25, and connected 75 by bolts or pins 26 engaging lateral extensions of the plates to form fulcrums for the side beams 12, which also consist of parallel bars or elements 12^a and 12^b, which may be connected at their forward ends by 80 loops 27, which in the construction illustrated are formed as integral parts of the elements 12^a and 12^b, to engage pivotally the portions of the bolts 26 between the planes of the parallel plates 24. The plow 85 standards 13 are interposed at intervals between the elements of the side beams, and said elements are connected at intervals by transverse bolts 28, the tightening of which serves to draw the elements into frictional 90 engagement with the interposed standards, and upper and lower front and rear bearing points or projections 29 and 30 may be provided on said side beam elements to engage the front and rear surfaces of the plow 95 standards to maintain the latter in their 100 proper adjusted position.

It will be understood that while turning shovels 31 are shown attached to said standards, any desired form of shovels may be 105 used in this connection, as for example the diamond shaped blade 32, which is attached to the forward colter standard 22 in the illustrations, and a full equipment of which may be provided with each cultivator. 110 Spacing blocks 33 may be interposed between the rear ends of the elements form-

ing the side beams, and vertically engaging said beams, as for example between the elements thereof, are pivoted bolts 34, which serve to pivotally connect therewith the remote extremities of the members 14^a and 14^b of the transverse adjusting bar 14. One or both of these elements should be slotted, as shown at 35, for engagement by the locking bolt 36 to maintain the elements in their adjusted relation and thus hold the side shovel-carrying beams in the desired rearwardly divergent positions with reference to the main or central beam.

The advantages in operation of a structure such as above described will be apparent to those skilled in the art, and particularly those engaged in the operation of devices of this character and to the manufacturer it will be equally obvious that the various members may be constructed with a minimum of mill work and by the use of tools ordinarily employed, machining being reduced to the minimum while the resulting structure, which is comparatively light in weight has its parts so disposed as to afford the maximum strength and resistance to the strains to which devices of this character are ordinarily subjected. The replacement or substitution of blades or shovels of different kinds or designed for

different treatments of the soil may be accomplished with facility, involving merely the loosening of the bolts by which the elements of the side beams are connected transversely, and the elements constituting the main and side beams and the connections between the same and including the transverse adjustable bar and the braces for the handles are of stock form, or may readily be produced from sheet or plate metal of the selected gage and may be adapted to the various purposes indicated with a minimum shaping or other treatment.

Having described the invention, I claim:

In a cultivator, a beam composed of spaced side bars, said side bars being provided at their edges with incisions and the material of the side bars adjacent the incisions being inwardly disposed to form tongues which lie between the side bars, standards lying between the side bars and between the tongues carried by the side bars and soil engaging elements carried by the standards.

In testimony whereof I affix my signature in presence of two witnesses.

ERVAN V. ALLEN.
